United States Patent

Des. 239,080

Patented Mar. 9, 1976

239,080

GENERAL PURPOSE SHEARS

Richard L. Stevenson, Los Angeles, Calif., assignor to
Pacific Metals Products Company, Sun Valley, Calif.

Filed May 8, 1974, Ser. No. 468,066

Term of patent 14 years

Int. Cl. D8—03

U.S. Cl. D8—5

FIG. 1

FIG. 2

FIG. 1 is a top plan view of general purpose shears embodying my new design; and

FIG. 2 is a side elevation of the general purpose shears of FIG. 1.

The hidden sides in FIGS. 1 and 2 are the same as the illustrated sides.

I claim:

The ornamental design for general purpose shears, substantially as shown and described.
